UNITED STATES PATENT OFFICE

FREDRIK W. HVOSELEE, OF KOHLER, WISCONSIN, ASSIGNOR TO KOHLER COMPANY, OF KOHLER, WISCONSIN, A CORPORATION OF WISCONSIN

RETURN BAFFLE FOR FLUE DOORS

Application filed October 18, 1930. Serial No. 489,504.

This invention has for its object to provide the flue door of a boiler or furnace with a return baffle for deflecting flue gases in the direction of turn of the flue passageways 5 at that point so as to contribute to the streamline effect and thus facilitate the movement of the gases and avoid the production of corners or projections causing eddy currents.

Another object of the invention is to make such a baffle of durable and inexpensive construction and capable of secure and ready attachment to the flue door and serving to protect the flue door from overheating.

With the above and other objects in view the invention consists in the return baffle for flue doors as herein claimed and all equivalents.

Referring to the accompanying drawings, 20 in which like characters of reference indicate the same parts in different views,

Fig. 1 is a sectional plan view of a boiler through the flue door thereof showing a baffle constructed in accordance with this 25 invention;

Fig. 2 is a vertical sectional view on the plane of line 2—2 of Fig. 1, and

Fig. 3 is an inner face view of the baffle itself.

In these drawings, 10 indicates a sectional boiler of a usual type having forwardly directed side flues 11, and a rearwardly directed central return flue 12 with a common flue space 13 in the front section 35 forming return bends connecting the side flues with the central flue and giving access to the flue spaces for cleaning through the flue door 14.

It is common practice to provide the back 40 of the flue door with protecting plates of various types to prevent excessive loss of heat through the flue door and the purpose of this invention is to utilize such a protecting plate as a baffle conforming with the streamline of the flow of gases in making the return bend from both side flues to the central return flue. To this end the protecting plate constitutes a baffle 15, which is preferably an iron casting having two parallel 45 cylindrically convex deflecting members 16

with top and bottom rearwardly extending flanges 17 on their inner faces and with top and bottom forwardly extending flanges 18 on their outer faces.

This baffle is secured to the back of the flue door 14 by having openings 19 at approximately the middle of the deflecting members 16 to receive lugs 20 projecting from the back of the flue door, as best seen in Fig. 2. Slight projections or bosses 21 are formed on the baffle above and below the openings 19 to form bearing points for contacting with the inner wall of the flue door and the baffle is held in contact at such points by the action of wedge pins 22 driven through vertical openings in the lugs 20 and guided in beveled notches 23 above and below the openings 19 and resting on projections 24. The baffle is thus securely mounted on the back of the flue door and, except for its points of contact therewith, is spaced therefrom and forms a guard for preventing overheating of the door.

The principal function of the baffle, however, is that of constituting deflecting surfaces in the path of the forwardly travelling gases from the side flues 11 for directing them inwardly to the central return flue 12 with a minimum amount of resistance due to eddy currents. The double convex 80 deflector conforms with the path of travel of the gases to present a streamline guide to exclude pockets or corners in which eddy currents may be formed and consequently the flow of gas is facilitated, improving the 85 draft and avoiding waste of heat.

The manner of mounting the baffle on the flue door makes for a permanent connection that will resist the action of heat and that may be readily released at any time that it 90 may be necessary or desirable and still the flue door is not marred by the presence of bolt holes and consequently may be enameled to present a neat and ornamental appearance.

What I claim as new and desire to secure by Letters Patent is:

1. A baffle for flue doors comprising a plate having means for attaching it to and spacing it from the inner side of a flue door,

said plate being of curved form for deflecting flue gases from one flue to another.

- 5 2. A baffle for flue doors comprising a plate forming a pair of contiguous concave surfaces and provided with means for attaching it to and spacing it from the inner side of a flue door, said surfaces serving to conform with the direction of current of gases from side flues to a central return flue to complete a streamline guide therefor.
- 10 3. In a boiler or furnace having side flues and a central return flue, a flue door giving access thereto, and a baffle comprising a plate attached to and spaced from the inner side of the door and forming a pair of contiguous concave surfaces conforming with the path of flow of gas from the side flue to the central return flue to form a streamline guide therefor.
- 15 4. In a boiler or furnace having side flues and a central return flue, a flue door for controlling access to a baffle comprising a plate having two contiguous cylindrical concave surfaces at the rear, top and bottom flanges extending rearwardly from said surfaces, top and bottom flanges extending forwardly from the junction between said surfaces, and means for securing the plate to
- 20 the inner side of the flue door.
- 25 5. In a boiler or furnace, a flue door, a baffle comprising a plate having a pair of contiguous cylindrical concave rearwardly directed surfaces, a pair of lugs formed on the inner side of the flue door entering through openings in the cylindrical surfaces, spacing projections formed on the baffle plate and bearing on the back of the flue door, and pins extending through openings in the lugs and engaging the baffle for holding it in place.

In testimony whereof I affix my signature.

FREDRIK W. HVOSLEF.
